ARTICLE HOLDER FOR AUTOMOBILES AND THE LIKE

Paul P. Scheurer, 1318 8th St., Wichita Falls, Tex.

Filed Jan. 18, 1960, Ser. No. 59,076

Term of patent 14 years

(Cl. D14—6)

Fig. 1 is a perspective view of the article holder for automobiles or the like taken from above and showing a side and an end thereof;

Fig. 2 is a view similar to Fig. 1, but is taken from the opposite side and end thereof.

The underside of the article holder which straddles the drive-shaft hump is substantially plain.

I claim:

The ornamental design for an article holder for automobiles or the like, as shown and described.
